MINING MACHINE

Clyde P. Baldwin, Claremont, N. H., assignor to
Sullivan Machinery Company, a corporation of
Massachusetts

Application October 24, 1932, Serial No. 639,289

28 Claims. (Cl. 262—30)

This invention relates to mining machines, and more particularly to improvements in the swinging mechanism for the cutter bar of a machine for mining coal.

An object of this invention is to provide an improved mining machine. Another object is to provide an improved coal mining machine of the longwall type having improved cutter bar swinging mechanism. A further object is to provide an improved swinging mechanism for the cutter bar of a longwall coal mining machine whereby the cutter bar may be swung in an improved manner wholly independently of the machine feeding means. Yet another object is to provide an improved cutter bar swinging mechanism having improved driving and controlling means whereby the cutter bar may be swung in either direction about its pivot in an improved manner. Still another object is to provide an improved cutter bar swinging mechanism for a coal mining machine of the flexibly fed, continuous cutter, bottom cutting floor cutter type, wherein the cutter bar may be swung about its pivot through improved motor operated mechanism wholly independently of the flexible feeding means. These and other objects of the invention will, however, hereinafter more fully appear.

In the accompanying drawings there are shown, for purposes of illustration, one form and a modification thereof which the invention may assume in practice.

In these drawings,—

Fig. 1 is a plan view of a longwall coal mining machine with which the preferred illustrative form of the improved bar swinging mechanism is associated.

Fig. 2 is a side elevational view of the mining machine shown in Fig. 1.

Fig. 3 is a central, longitudinally extending, vertical sectional view taken substantially on line 3—3 of Fig. 1.

Fig. 4 is a transverse vertical sectional view taken substantially on line 4—4 of Fig. 3.

Figs. 5, 6 and 7 are detail views illustrating the improved control means for the bar swinging mechanism.

Fig. 8 is a detail sectional view taken on line 8—8 of Fig. 5.

Fig. 9 is a detail sectional view taken on line 9—9 of Fig. 3.

Fig. 10 is an enlarged detail sectional view of a portion of the bar swinging mechanism shown in Fig. 3.

Fig. 11 is a horizontal sectional view taken

substantially on line 11—11 of Fig. 3, with the cutter bar swung into a different position.

Fig. 12 is a horizontal sectional view taken substantially on line 12—12 of Fig. 3.

Fig. 13 is an enlarged plan view of the machine cutter head showing the improved bar swing control means, a portion of the bar swinging mechanism being shown in horizontal section.

Fig. 14 is a horizontal sectional view through the machine cutter head, illustrating a modified form of construction.

Fig. 15 is a detail view taken on line 15—15 of Fig. 14.

Fig. 16 is a central, longitudinally extending, vertical sectional view taken substantially on line 16—16 of Fig. 14.

Fig. 17 is a transverse vertical sectional view taken substantially on line 17—17 of Fig. 16.

Fig. 18 is a detail view taken on line 18—18 of Fig. 14.

Fig. 19 is a vertical sectional view taken on line 19—19 of Fig. 14.

In the illustrative form of the invention shown in Figs. 1 to 13, inclusive, the improved bar swinging mechanism is shown embodied in a coal mining machine of the flexibly fed, continuous cutter, bottom cutting type, herein a longwall machine generally comprising a machine frame 1

having a plane bottom surface 2 on which the machine is slidably supported for movement over the mine floor. As is usual in longwall machines, pivotally mounted on the rear end of the machine frame at 3 for horizontal swinging movement relative thereto, is a horizontal plane cutter bar 4 having guided for circulation about its margin a usual cutter-bit-carrying cutter chain 5,

the cutter bar being swingable to substantially right-angle positions at either side of the machine frame and to a central position extending longitudinally of the machine frame. The ma-

chine is fed over the mine floor by means of a horizontal feed drum 6 located at the front end of the machine and cooperating with a usual feed cable 7 anchored to an extraneous abutment located adjacent the coal face in advance of the ma-

chine. Arranged intermediate the machine cutter head 8 on which the cutter bar is pivotally mounted, and the feed frame 9 which houses the feeding mechanism, is a horizontal motor 10 hav-

ing its power shaft operatively connected to the cutter chain and the feed drum and driving, through improved mechanism to be later de-

scribed, the improved cutter bar swinging mech-

anism. In the present construction, connectible to the rear end of the motor power shaft, as by a

50

45

55

usual sliding clutch 11, as shown in Fig. 3, is a bevel pinion 12 meshing with a bevel gear 13. Rotatable with and driven by the gear 13 is a spur gear 14 meshing with a spur gear 15 keyed 5 to a vertical shaft 16. Also keyed to this vertical shaft is a chain sprocket 17 which engages and drives the cutter chain 5 in a well known manner. As the particular construction of the feeding mechanism has no relation to the present invention, and as the improved bar swinging mechanism may be associated with mining machines of various types other than that shown, further illustration and description of the machine structure are considered unnecessary.

15 In the preferred form of the improved bar swinging mechanism there is shown fixed to the cutter head 8, as by bolts 20, a worm gear segment 21 (most clearly shown in Fig. 11) having the pitch circle of its teeth struck from the bar 20 pivot axis; and meshing with the teeth of this worm gear segment is a transverse worm 22 journaled on a horizontal axis on the cutter bar 4. This worm, as hereinafter described, is connectible to a horizontal shaft 23, herein made hollow 25 to receive a reciprocatory control shaft 24, and the ends of this shaft 23 are journaled within suitable bearing sleeves 25, 25 which also form supports for the worm 22, the sleeves being journaled within a combined bearing bracket and gear 30 housing 26, herein secured to the cutter bar and within which the worm and worm shaft are arranged. This bracket is herein formed with a detachable cover portion for obtaining access to the worm and its associated mechanism, as shown 35 in Figs. 3 and 4. The worm 22 may be rotated in either of opposite directions by the motor while the latter runs continuously in the same direction, and this improved worm rotating means comprises an eccentric 27, herein formed on the 40 hub of the chain sprocket 17, as shown in Fig. 3; and surrounding this eccentric is an eccentric strap 28 formed on a reciprocatory rod or bar 29 guided at 30 within a groove on the cutter bar. This rod 29 is provided with a transverse groove 45 31 for receiving a cross member 32 guided at its ends within elongated slots 33 formed in the opposite vertical side walls of the bracket 26. The transverse member 32 is herein in the form of a trunnion block, and engaging trunnions 34, 34 50 formed on its opposite ends are forked portions 35 of arms or levers 36, 36 keyed to the opposite ends of the worm shaft 23. The means for connecting the worm 22 to the shaft 23 comprises an intermittent grip device, herein a reversible cam and 55 roller clutch generally designated 37; and this clutch comprises two sets of rollers, the rollers of one set being numbered 38 and the rollers of the other set being numbered 39; and these rollers are arranged within and engage the bore 40 of the worm 22. These rollers are arranged within recesses 41 formed in the shaft 23, as shown 60 in Fig. 3, and the recesses are formed with inclined surfaces 42 converging outwardly at each side of the shaft. These recesses are formed 65 with enlarged chambers 43 which receive the rollers when the latter are in their released or inoperative position. The shaft 23 is also formed with a transverse slot 44 having arranged therein reciprocable roller releasing plungers or cam release elements 45 and 46, the plungers 45 coacting 70 with the set of rollers 38 and the plungers 46 coacting with the rollers 39. For projecting the roller releasing plungers or for releasing the same, there are formed on the shaft 24, in parallel longitudinal planes, notches 47, 48, 49 and 50, the

notches 47, 50 and 48, 49 being arranged in the same longitudinally spaced transverse planes but at opposite sides of the shaft 24, as shown in Fig. 8. The rollers are normally maintained in their outermost or active position by means of spring pressed plungers 51 guided within bores formed in the shaft 23, as shown in Fig. 9. When the parts are in the position shown in Fig. 3, the set of rollers 38 is held released by the plungers 45; and upon oscillation of the shaft 23 through the rod and eccentric mechanism above described, the rollers 39 engage the inclined surfaces 42 of the recesses and the bore 40 of the worm with a wedging action, thereby to effect intermittent rotation of the worm in a clockwise direction, as viewed in Fig. 3; and as a result the cutter bar is swung from left to right. When the control shaft 24 is moved axially into its opposite or reverse position, the semi-circular projections 52 formed on the roller release plungers 45 drop into the slots 48, 49 while the plungers 46 are projected outwardly, thereby to release the rollers 39 and to render the rollers 38 effective; and upon oscillation of the shaft 23 the worm is intermittently rotated in the reverse or counterclockwise direction, as viewed in Fig. 3, thereby to effect bar swing from right to left. When the control shaft 24 is in the position shown in Fig. 6, that is, with all the roller release plungers in their outer projected position, the rollers are held in their released position in the enlarged chambers 43 of the recesses, thereby wholly disconnecting the oscillatory shaft 23 from the worm, the shaft 23 freely oscillating within the worm when the rollers are thus positioned. When the parts are thus disposed, the cutter bar is rigidly locked against swinging movement by the self-locking teeth of the worm engaging the teeth of the worm gear segment. The shape and proportions of the members 45, 46 will be selected to prevent their coaction with the rollers to wedge, and to cause them to serve as mere positioning members.

For limiting swinging movement of the cutter bar and for controlling the roller release shaft 24 at will, there are provided appropriately located abutments 55 and 56, and the opposite ends of the control shaft 24 are provided with buttons 57 for engaging these abutments. When the cutter bar is swung from the full line position shown in Fig. 1 to the dotted line position in that figure, and as the cutter bar reaches the dotted line position, the button on the adjacent end of the shaft 24 engages the abutment 56, and upon continued swinging movement of the cutter bar the shaft 24 is shoved inwardly into the position shown in Fig. 6, thereby releasing the roller release plungers and disconnecting the bar swinging mechanism from its drive. When the cutter bar is swung from the dotted line position shown in Fig. 1 to the full line position in that figure, the abutment 55 acts to effect release of the bar swinging mechanism from its drive in a similar manner. In this instance, the abutments 55, 56 are made adjustable and are provided with suitable operating mechanism to enable connection of the bar swinging mechanism to its drive at will. The abutments 55, 56 are respectively pivotally mounted at 58, 58 on the cutter head frame 8, and each has pivotally connected thereto at 59 a plunger 60 suitably guided within a strap 61. The inner adjacent ends of the elements 60 are rounded at 62 for engagement with cam surfaces 63 formed on a rotatable cam member 64, herein rotatably mounted at 65 about an axis coincident with the 75

axis of bar swing, as shown in Fig. 3, and located at the top of the cutter head frame. For rotating this cam member there is provided a lever 66 pivotally mounted at 67 on and overlying the top of the machine frame and having its inner end 68 formed to fit a socket 69 on the cam member. The outer end of this lever is provided with a suitable handle 70, and the lever is guided by means of a transverse guide bar 71 attached to the top of the feed frame, as shown in Fig. 1. When the handle 70 of the lever 66 is swung laterally from the position shown in Fig. 1, the cam member 64 is rotated to cause the cam surfaces 63 thereof to project the plungers 60 outwardly, thereby to swing the abutment members 55, 56 inwardly about their pivots. Swinging movement of the abutment 55 causes the roller release shaft 24 to be slid inwardly into its connected position, thereby connecting the bar swinging mechanism to its drive, and as a result, the cutter bar may be swung from the full line position shown in Fig. 1 to the dotted line position in that figure. When the cutter bar is in the dotted line position in Fig. 1, the abutment 56 may be operated in a similar manner to connect the bar swinging mechanism to its drive. When it is desired to swing the cutter bar to the opposite side of the machine, the abutments 55, 56 are detached from the machine cutter head and are replaced by similar abutments 72, 73, and the abutment swinging parts are correspondingly reversed. Suitably located bolt holes are provided in the cutter head frame for receiving the holding bolts for the abutments 72 and 73 and the guide straps 61 for the plungers 60, as shown in Fig. 13. When it is desired to swing the cutter bar from one extreme position at one side of the machine to an extreme position at the opposite side of the machine, the abutments 55, 56 and their associated swinging mechanism are removed from the machine, and at this time suitable adjustable abutments 74, 75 threaded secured within bosses 76 integral with the cutter head frame at the opposite sides of the machine, act to release the bar swinging mechanism when the cutter bar reaches each extreme limit of swinging movement, as shown in full and dotted lines in Fig. 11. When it is desired to position the cutter bar in its central position, as indicated in dotted lines in Fig. 11, the bar swinging mechanism may be manually released when it assumes its central position. From the foregoing description, it will be evident that the cutter bar may be swung in either direction about its pivot wholly independently of the machine feeding means and while the motor and cutting mechanism operate continuously in the same direction, the improved reversible swinging mechanism being operable at will to effect power swing of the cutter bar. It will also be evident that by the provision of the improved adjustable abutment mechanism the bar swinging mechanism may be automatically disconnected from its drive when the cutter bar reaches its limit of swinging movement in either direction, and may be connected to its drive at will.

In the modified form of the invention shown in Figs. 14 to 19, inclusive, the cutter chain 5 is driven from the motor power shaft through a spur pinion 88 meshing with a spur gear 81, which in turn drives a spur pinion 82 meshing with a spur gear 83 fixed to a longitudinally extending shaft 84. This shaft, as shown in Fig. 14, is connectible by a sliding cutter chain clutch 85 to an

aligned shaft 86. Fixed to the shaft 86 is a worm 87 meshing with a worm wheel 88 keyed to a vertical shaft 89. Also keyed to this shaft is a chain sprocket 90 which engages and drives the cutter chain 5 in a well known manner. The improved bar swinging mechanism in this form of the invention comprises a spur gear 91 meshing with the motor pinion 88 and driving a spur pinion 92 fixed to a longitudinal shaft 93 and meshing with a spur gear 94 journaled on a longitudinally extending shaft 95 herein arranged at the opposite side of the machine from the shaft 86. Also fixed to the shaft 93 and driven thereby is a spur pinion 96 meshing with an intermediate gear 97 in turn driving a pinion 98 meshing with a spur gear 99 also journaled on the shaft 95. It will thus be seen that the spur gears 94, 99 rotate in opposite directions and constitute a reversing mechanism for the shaft 95, and these gears are selectively connectible to the shaft 95 by multiple disc clutches 100 and 101, respectively. Fixed to the shaft 95 is a worm 102 meshing with a worm wheel 103 secured, as by screws 104, to the cutter bar 4, as shown in Fig. 15. Keyed to the shaft 89 is an eccentric member or disk 105, and engaging an eccentric groove 104^a formed in the upper face of this eccentric member is a roller 105^a carried by a lever 106 pivotally mounted at 107 and connected at 108 to a shiftable clutch applying member 109 slidably mounted on the shaft 95 intermediate the clutches 100 and 101. The pivotal mounting 107 for the clutch operating lever is made adjustable, and this adjusting means comprises, as shown in Fig. 19, a vertical shaft 110 having a suitable socket 111 for receiving a suitable turning instrument. Keyed to the lower end of this shaft is a bevel gear 112 meshing with a bevel gear 113 herein formed integral with a nut member 114 suitably journaled at 115 within the machine cutter head. This nut member threadedly engages a screw shaft 116, and slidably mounted on this shaft is a trunnion member 117 to which the clutch operating lever is pivotally connected. The member 117 is yieldably positioned on the shaft by washers 117^a and 117^b engaging shoulders 118 and 118^a on the shaft and abutting the opposite ends of the member 117 when the latter is in its central position shown. Coiled springs 119 and 119^a encircling the shaft and acting on the washers at that time yieldably maintain the lever 106 in the central or neutral position as shown in Fig. 19. The tension of the springs may be adjusted by collars 119^b threaded on the shaft. The shaft 116 is guided at 120 within the machine cutter head. It will thus be seen that when the shaft 110 is rotated, the screw shaft 116 is moved axially in one direction or the other to move the pivotal mounting 107 for the clutch operating lever into different positions against the tension of the opposing spring. For instance, when the pivotal mounting 107 is shifted in one direction, the clutch 101 may be operated, while when the pivotal mounting is shifted in its opposite position, the clutch 100 may be operated. As the eccentric member 105 is rotated during drive of the cutter chain, the lever 106 is oscillated about its pivotal mounting 107, thereby to effect intermittent application and release of the desired friction clutch. As a result, the shaft 95 may be intermittently rotated, and through the worm gearing 102, 103 the cutter bar may be swung about its pivot in either direction under the control of the reverse frictions 100, 101. In this form of the invention the intermittently rotat-

able worm 102 functions in a manner similar to the intermittently rotatable worm 22 of the preferred form of the invention above described, and when released from the drive acts as a lock for 5 the cutter bar.

As a result of this invention, it will be noted that an improved cutter bar swinging mechanism is provided for a coal mining machine of the flexibly fed, continuous cutter, bottom cutting type, 10 whereby the cutter bar may be swung in either direction about its pivot wholly independently of the machine feeding means and without reversal of the machine driving motor and cutting mechanism. It will further be noted that an 15 improved cutter bar swinging mechanism is provided which is of an extremely simple nature and which may be operated and controlled in an improved manner. These and other uses and advantages of the improved bar swinging mechanism 20 will be clearly apparent to those skilled in the art.

While there are in this application specifically described one form and a modification thereof which the invention may assume in practice, it 25 will be understood that this form and modification are shown for purposes of illustration, and that the invention may be further modified and embodied in various other forms without departing from its spirit or the scope of the appended 30 claims.

What I claim as new and desire to secure by Letters Patent is:—

1. In a mining machine, a machine frame, a 35 cutter bar pivotally mounted thereon, and mechanism for swinging said bar about its pivot including cooperating gear elements on said bar and frame respectively, and an intermittent grip device for effecting rotation of one of said gear elements relative to the other, said grip device 40 being arranged within one of said gear elements.

2. In a mining machine, a machine frame, a cutter bar pivotally mounted thereon, mechanism for swinging said bar about its pivot including 45 cooperating gear elements on said bar and frame respectively and an intermittent grip device mounted to swing with said cutter bar for effecting rotation of said gear element on said bar relative to said gear element on said frame, and means for automatically releasing said grip device upon a predetermined swinging movement 50 of said cutter bar.

3. In a mining machine, a machine frame, a cutter bar pivotally mounted thereon, mechanism for swinging said bar about its pivot including 55 cooperating gear elements on said bar and frame respectively and an intermittent grip device mounted to swing with said cutter bar for effecting rotation of said gear element on said bar relative to said gear element on said frame, and abutment means on said frame for automatically releasing said grip device upon a predetermined swinging movement of said bar.

4. In a mining machine, a machine frame, a cutter bar pivotally mounted thereon, mechanism 65 for swinging said bar about its pivot including cooperating gear elements on said bar and frame respectively and an intermittent grip device for effecting rotation of one of said gear elements relative to the other, abutment means for automatically releasing said grip device upon a predetermined swinging movement of said bar, and means associated with said abutment means for actuating the latter to effect connection of said grip device in driving relation with said rotatable 70 gear element.

5. In a mining machine, a machine frame, a cutter bar pivotally mounted thereon, mechanism for swinging said bar about its pivot in either of opposite directions including cooperating gear elements on said bar and frame respectively and a reversible intermittent grip device for effecting rotation of one of said gear elements relative to the other in either of opposite directions, abutment means for automatically releasing said grip device upon predetermined swinging movement of said bar in either of opposite directions, and means associated with said abutment means for actuating the latter to effect connection of said grip device in driving relation with said rotatable gear element. 15

6. In a mining machine, a machine frame, a cutter bar pivotally mounted thereon, and mechanism for swinging said bar about its pivot including cooperating gear elements on said bar and frame respectively, and means for effecting 20 rotation of one of said gear elements relative to the other including an intermittent grip device, and an eccentric operated mechanism for actuating said device including a rotatable eccentric member arranged with its axis of rotation coincident with the bar pivot axis, a reciprocatory rod actuated thereby and an oscillatory element actuated by said rod. 25

7. In a mining machine of the floor cutter type, a machine frame adapted to rest upon and slide in any direction over the mine floor, flexible feeding means for the machine, a kerf cutting cutter bar pivotally mounted on said frame, mechanism independent from said flexible feeding means for swinging said bar about its pivot including cooperating gear elements on said bar and frame respectively and a speed reducing device including a final driving element rotatable relative to and mounted to swing with said cutter bar for effecting rotation of said gear element on 40 said bar relative to said gear element on said frame, and means for automatically releasing said device upon a predetermined swinging movement of said cutter bar. 30

8. In a mining machine, a machine frame, a cutter bar pivotally mounted thereon, mechanism for swinging said bar about its pivot including 45 cooperating gear elements on said bar and frame respectively and a speed reducing device for effecting rotation of one of said gear elements relative to the other, abutment means for automatically releasing said device upon a predetermined swinging movement of said bar, and means associated with said abutment means for actuating the latter to effect connection of 50 said device in driving relation with said rotatable gear element. 55

9. In a mining machine, a machine frame, a cutter bar pivotally mounted thereon, mechanism for swinging said bar about its pivot in either of opposite directions including cooperating gear elements on said bar and frame respectively and a reversible speed reducing device for effecting rotation of one of said gear elements relative to the other in either of opposite 65 directions, abutment means for automatically releasing said device upon predetermined swinging movement of said bar in either of opposite directions, and means associated with said abutment means for actuating the latter to effect 70 connection of said device in driving relation with said rotatable gear element.

10. In a mining machine, a machine frame, a cutter bar pivotally mounted thereon, mechanism for swinging said bar about its pivot in 75

- cluding cooperating gear elements on said bar and frame respectively, an intermittent grip device for effecting rotation of one of said gear elements relative to the other, means for driving 5 said device, and means operable at will for connecting said device in or releasing the same from driving relation with said rotatable gear element including a rotatable operating element coaxial with the bar pivot.
- 10 11. In a mining machine, a machine frame, a cutter bar pivotally mounted thereon, mechanism for swinging said bar about its pivot including cooperating gear elements on said bar and frame respectively and an intermittent grip device for 15 effecting rotation of one of said gear elements relative to the other, and means operable at will for connecting said device in or releasing the same from driving relation with said rotatable gear element including a rotatable operating element 20 coaxial with the bar pivot and actuating means for said operating element operable from the end of the machine remote from the cutter bar.
12. In a mining machine, a machine frame, kerf cutting mechanism thereon including a pivoted 25 cutter bar, cutting elements on said bar and driving means for said cutting elements including a driving gear coaxial with the bar pivot and a coaxial element driven thereby for engaging the cutting elements, and mechanism for swinging 30 said bar about its pivot including cooperating gear elements on said bar and frame respectively, and means actuated by an element of said cutter element driving means for effecting intermittent 35 rotation of one of said gear elements relative to the other and including an eccentric mechanism arranged between said gear and said cutter element engaging element and intermittent devices actuated by said eccentric mechanism and mounted to swing with said cutter bar.
- 40 13. In a mining machine, a machine frame, kerf cutting mechanism thereon including a pivoted cutter bar, cutting elements on said bar and driving means for said cutting elements including a driving gear coaxial with the bar pivot and a 45 coaxial element driven thereby for engaging the cutting elements, and mechanism for swinging said bar about its pivot including cooperating gear elements on said bar and frame respectively, and means actuated by an element of said cutter element driving means for effecting intermittent 50 rotation of one of said gear elements relative to the other and including an eccentric mechanism arranged between said gear and said cutter element engaging element, said eccentric mechanism 55 including an eccentric and a longitudinally reciprocable rod guided within said frame and actuated by said eccentric and intermittent devices actuated by said eccentric mechanism and mounted to swing with said cutter bar.
- 60 14. In a mining machine, a machine frame, kerf cutting mechanism thereon including a pivoted cutter bar, cutting elements on said bar and driving means for said cutting elements including a driving gear coaxial with the bar pivot and a 65 coaxial element driven thereby for engaging the cutting elements, and mechanism for swinging said bar about its pivot including cooperating gear elements on said bar and frame respectively, and means actuated by an element of said cutter element driving means for effecting intermittent 70 rotation of one of said gear elements relative to the other and including an eccentric mechanism arranged between said gear and said cutter element engaging element, said eccentric mechanism 75 including an eccentric, a longitudinally reciprocable rod guided within said frame and actuated by said eccentric and an oscillatory element actuated by said rod, said rod and oscillatory element mounted to swing with said cutter bar.
15. In a mining machine, a machine frame, a cutter bar pivotally mounted thereon, and mechanism for swinging said bar about its pivot including cooperating gear elements on said bar and frame respectively, and an intermittent grip device arranged within one of said gear elements 10 for effecting intermittent rotation of one of said gear elements relative to the other, said device including a member having oscillatory movement about the axis of the gear element within which said device is arranged, grip elements actuated 15 by said oscillatory element for gripping said gear element, and means coaxial with said oscillatory element for connecting the grip elements in or releasing the same from driving relation with said gear element and including a controlling 20 plunger arranged within and movable axially of said oscillatory element.
16. In a mining machine, a frame, a plane cutter bar pivotally mounted thereon to swing in its plane relative thereto, motor operated means including driving elements mounted to swing with said cutter bar for swinging the cutter bar about its pivot to form an arcuate kerf in the mine wall, and means on said frame for automatically disconnecting said motor operated means upon a 25 predetermined swinging movement of said bar.
17. In a mining machine, a machine frame, a cutter bar pivotally mounted thereon, motor operated means for swinging said cutter bar about its pivot including bar swing driving connections 30 including a friction disc clutch, and means for automatically loading and releasing the discs of said clutch including an eccentric arranged with its axis alined with the bar pivot axis, and clutch operating means actuated by said eccentric. 35
18. In a mining machine, a machine frame, a cutter bar pivotally mounted thereon, motor operated devices for swinging said cutter bar about its pivot in either of opposite directions including cutter bar swinging connections 40 including friction disc reversing clutches, and means for intermittently loading and unloading the discs of one of said clutches to effect bar swing in one direction or the other of said clutches to effect bar swing in the opposite direction including an eccentric arranged with its axis alined with the bar pivot axis, and clutch operating means actuated by said eccentric. 45
19. In a mining machine, a machine frame, a cutter bar pivotally mounted thereon, and motor operated means for actuating said kerf cutter including cutter driving gearing, and motor operated devices for swinging said cutter bar about its pivot including bar swing driving gearing entirely independent from said cutter driving gearing and variable speed driving means adjustable at will during bar swing for intermittently driving said gearing through a wide range of intermittent swinging speeds between zero and a predetermined maximum and continuously driving 50 said gearing at said predetermined maximum low speed.
20. In a mining machine of the floor cutter type, a machine frame adapted to rest upon and slide in any direction over the mine floor, flexible feeding means for the machine, a kerf cutting cutter bar pivotally mounted on said frame, and motor operated means entirely independent from said flexible feeding means for swinging said cutter bar about its pivot including a continuous and 55

- intermittent bar swinging mechanism operatively connected to said bar, and associated means for varying the operation of said intermittent mechanism for varying the rate of bar swing, said associated means being adjustable at will to obtain a wide range of intermittent swinging speeds between zero and a predetermined maximum and continuous swing at said predetermined maximum low speed.
21. In a mining machine of the floor cutter type, a machine frame adapted to rest upon and slide in any direction over the mine floor, flexible feeding means for the machine, a kerf cutting cutter bar pivotally mounted on said frame, motor operated means entirely independent from said flexible feeding means for swinging said cutter bar about its pivot including an intermittent bar swinging mechanism operatively connected to said bar and including a friction clutch through which power is transmitted to effect bar swing, means for intermittently applying and releasing said clutch at predetermined time intervals, and associated means for varying the intervals of application and release of said clutch to vary the rate of bar swing.
22. In a mining machine of the longwall floor cutter type, a low compact machine frame adapted to rest upon and slide in any direction over the mine floor, flexible feeding means for the machine, a kerf cutting cutter bar pivotally mounted on said frame at one end thereof, motor operated means entirely independent from the flexible feeding means for swinging said cutter bar about its pivot, and means operable from the end of the machine frame remote from the bar pivot for controlling said bar swinging means.
23. In a mining machine, in combination, machine feeding means, kerf cutting means including a cutter bar pivotally mounted for swinging movement, and motor operated means operable independently of the machine feeding means for swinging said cutter bar about its pivot including bar swinging driving connections, said driving connections including a friction disc clutch, and means actuated by an element of said motor operated means for intermittently loading and unloading the discs of said clutch at timed intervals.
24. In a mining machine, in combination, ma-
- chine feeding means, kerf cutting means including a cutter bar pivotally mounted for swinging movement, and motor operated means operable independently of the machine feeding means for swinging said cutter bar about its pivot in either of opposite directions including alternatively operable friction disc reversing clutches and means actuated by an element of said motor operated means for intermittently loading and unloading the discs of either clutch.
25. In a mining machine, a machine frame, a cutter bar pivotally mounted thereon, motor operated means for swinging said cutter bar about its pivot including an intermittent grip device mounted to swing with said cutter bar, and means arranged coaxially with said device for reversing the direction of operation thereof at will.
26. In a mining machine, a machine frame, a cutter bar pivotally mounted thereon, and motor operated means for swinging said cutter bar about its pivot including an intermittent grip device and a plunger arranged coaxially with said device for releasing said grip device at will.
27. In a mining machine, a machine frame, a cutter bar pivotally mounted thereon, and motor operated means for swinging said cutter bar about its pivot including a driven member having a bore, a ratchet device arranged within said bore, and a plunger arranged coaxially with said ratchet device for releasing the same at will.
28. In a mining machine, a machine frame, a cutter bar pivotally mounted thereon, a driving motor, and mechanism operated by said motor for swinging said bar about its pivot selectively in opposite directions including cooperating gear elements, one on said bar and one on said frame, and means for effecting rotation of one of said gear elements relative to the other to effect bar swing including in coaxial relation with said rotated gear element selectively reversely effective intermittent-motion transmitting means operative to effect step-by-step bar swing in either direction while said motor operates continuously in a single direction, and means adjustable in a direction longitudinally of the axis of said rotatable gear element for controlling said intermittent-motion transmitting means to determine the direction of rotation of said gear.

CLYDE P. BALDWIN.

CERTIFICATE OF CORRECTION.

Patent No. 2,053,259.

September 8, 1936.

CLYDE P. BALDWIN.

It is hereby certified that error appears in the printed specification of the above numbered patent requiring correction as follows: Page 3, second column, line 62, for the word "direction" read position: page 5, second column, line 37, claim 17, for "releasing" read unloading; and that the said Letters Patent should be read with these corrections therein that the same may conform to the record of the case in the Patent Office.

Signed and sealed this 1st day of December, A. D. 1936.

Henry Van Arsdale

(Seal)

Acting Commissioner of Patents.
